UNITED STATES PATENT OFFICE.

JOSEPH McNEAL, OF LAPORTE CITY, IOWA.

TRACTION-WHEEL.

No. 846,689.

Specification of Letters Patent.

Patented March 12, 1907.

Application filed June 9, 1906. Serial No. 321,083.

To all whom it may concern:

Be it known that I, JOSEPH McNEAL, a citizen of the United States, residing at La-
porte City, in the county of Blackhawk and
5 State of Iowa, have invented a new and
useful Traction-Wheel, of which the follow-
ing is a specification.

This invention has relation to traction-
wheels; and it consists in the novel construc-
10 tion and arrangement of its parts, as herein-
after shown and described.

The object of the invention is to provide a
wheel adapted to be used on traction-en-
gines or agricultural implements, said wheel
15 having a number of tractors which are adapt-
ed to be extended or drawn in with relation
to the wheel-rim. A means is provided for
extending or drawing in the said tractors
while the wheel is at rest, and also means is
20 provided for extending or drawing in the
said tractors while the wheel is rotating.
Means is also provided for adjusting or vary-
ing the length of the ends of the tractors that
project beyond the wheel-rim.

25 In the accompanying drawing, Figure 1 is
a side elevation of the traction-wheel, partly
in section. Fig. 2 is a transverse sectional
view of the traction-wheel; and Fig. 3 is a
side elevation of the rear portion of a trac-
30 tion-engine, illustrating the application of
the traction-wheel.

The wheel-rim 1 is provided with a num-
ber of perforations or openings 2, and at-
tached to the inner side of said wheel-rim and
35 adjacent to said perforations are the guides
3, said guides being perforated and having
their perforations registering with the per-
forations 2. The tractors 4 are adapted to
extend radially with relation to the wheel-
40 rim when in extended position and extend
tangentially with relation to the said wheel-
rim when in withdrawn position. The said
tractors are pointed at their outer ends, as at
5, and gradually increase in thickness toward
45 their inner ends. The castings 6 are bolted
together about the hub 7 of the said wheel.
Said castings are adapted to describe partial
rotation about the said hub.

The inner ends of the tractors 4 pass be-
50 tween the side plates 8 8 of said castings and
are pivotally attached thereto by means of
the bolts 9. The plates 8 8 are provided with
a number of bolt-perforations 10, which ex-
55 tend in radial lines. By means of these per-
forations, arranged, as stated, in sets, the tra-
ctors 4 may be adjusted longitudinally with

relation to the said plates 8 8. When it is
desired that the tractor-points 5 should pro-
ject well into the ground, the inner ends of
the tractors are secured to the plates 8 8 by
60 passing the bolt 9 through the outer perfora-
tion 10 of the set of perforations. When it
is desired that the tractor-points 5 should
have but slight engagement with the ground,
the inner ends of said tractors are secured by
65 means of said bolt 9 at the innermost perfora-
tions 10. Thus a means is provided for ad-
justing said tractors longitudinally and at
the same time affording a positive support
and attaching means for the same. 70

It is obvious that in view of the fact that
the tractors 4 are pivotally attached to the
plates 8 8 at points between the circumfer-
ences and centers of the said plates that if
the said plates are rotated slightly upon the
75 hub 7 that the outer pointed ends 5 of the
tractors 4 will be withdrawn within the pe-
riphery of the wheel-rim 1. To accomplish
this, one or more of the plates 8 is provided
with the handles 11, by means of which the 80
said plates may be partially rotated, and
when in proper position are fixed with relation
to the wheel-hub 7 by means of the pin
12, which is passed through the perforation
13 in the side of the hub 7 and through a per-
85 foration 14 in the side of the plate 8. Said
plate 8 is also provided with a perforation 15,
which is adapted to receive said pin 12 when
the tractors are in extended positions. It
will thus be seen that when the plates 8 are 90
in position that they are oppositely secured
in such positions.

The plates 8 8 are adapted to be partially
rotated by the means as above described
when the wheel is at rest. A means is also
95 provided for partially rotating the said
plates 8 8 while the wheel is in motion. Said
means consists of the pin 16, which enters
the opening 17 in one of the plates 8 and is
provided with a spring, which engages the 100
side of said opening, and thereby affords a
friction means for retaining the pin 16 in the
opening 17. The link 18 connects the lever
19 with the pin 16. Said lever is suitably
fulcrumed at any convenient point on the 105
frame of the traction implement. As the
traction-wheel 1 rotates the lever 19 vibrates
back and forth upon its fulcrum-point, and
in order to move the tractors with relation to
the rim of the wheel 1 the lever 19 is either 110
held stationary for a short space of time
while the wheel 1 is rotating or the lever is

moved manually in the direction in which it is traveling faster than the rate at which it normally moves. Thus the pin 16 partially rotates the plates 8 with relation to the wheel 1, and the tractors 4 are also relatively moved.

Having described my invention, what I claim as new, and desire to secure by Letters Patent, is—

- 10 1. A traction-wheel having openings at its rim, tractors having ends located in said openings, a plate rotatably mounted upon the wheel-hub, said plate having perforations which extend in radial lines with relation thereto, and means for securing the inner ends of the tractors to said plate at the said perforations thereof.
- 15 2. A traction-wheel having perforations at its rim, tractors passing through said perforations, a plate rotatably mounted upon the wheel-hub, the inner ends of said tractors being adjustably pivoted to said plate, and lever-operated means operatively connected with said plate and adapted to partially rotate the same.
- 20 3. A traction-wheel having openings at its rim, tractors extending through said openings, a plate rotatably mounted upon the wheel-hub, the inner ends of said tractors

being pivotally and adjustably attached to 30 said plate, a means for partially rotating said plate while the wheel is at rest, and a means for partially rotating said plate while the wheel is in motion.

4. A traction-wheel having openings 35 provided in its rim, tractors located in said openings, plates connected together and being rotatably mounted upon the wheel-hub, the inner ends of said tractors being adjustably pivoted between said plates, and means for 40 partially rotating said plates.

5. A traction-wheel having openings at its rim, tractors located in said opening, plates oppositely arranged and connected together and being rotatably mounted upon the wheel-hub, the inner ends of said tractors being adjustably pivoted between said plates, a means for partially rotating said plates, and a means for fixing said plates with the wheel-hub after they have been partially rotated. 45

In testimony that I claim the foregoing as my own I have hereto affixed my signature in the presence of two witnesses.

JOSEPH McNEAL.
